UNITED STATES PATENT OFFICE.

FRANK J. BOYLE, OF GALVESTON, TEXAS.

TOY.

1,113,874.

Specification of Letters Patent.

Patented Oct. 13, 1914.

Application filed May 29, 1914. Serial No. 841,854.

To all whom it may concern:

Be it known that I, FRANK J. BOYLE, a citizen of the United States, residing at Galveston, in the county of Galveston and State of Texas, have invented new and useful Improvements in Toys, of which the following is a specification.

The invention relates to toys and has for an object to provide a toy particularly adapted for the amusement of small children, the toy being arranged and constructed so that it can be readily operated.

The invention contemplates, among other features, the provision of a toy which contains templates relatively movable members having figures associated therewith and whereby the operation of the members will result in an operation of the figures, causing the figures to coöperate in their movements to produce an amusing result.

In the further disclosure of the invention reference is to be had to the accompanying drawings, constituting a part of this specification, in which similar characters of reference denote corresponding parts in all the views, and in which:

Figure 1 is a front elevation of the device showing the same in one position, with the middle figure tilted forwardly; Fig. 2 is a vertical longitudinal sectional view taken through the device with the middle figure slightly rearward of its normal position; Fig. 3 is a fragmentary rear elevation of the device; Fig. 4 is a vertical transverse sectional view taken substantially on the line 4—4 in Fig. 1, showing substantially the manner of mounting the figures.

Referring more particularly to the views, I provide a plurality of similar members 10 and 11 formed in the nature of bars and preferably made of wood, said members 10 and 11 being arranged in superposed relation, with the extremity of one member projecting beyond the inner end of the other member. A series of figures 12, 13 and 14 are associated with the members 10 and 11 in that the figure 12 has pivotal connection at the point 15 with the member 10 and pivotal connection at the point 16 with the member 11, whereas the figure 13 has pivotal connection with the members 10 and 11 at the points 17 and 18 respectively, and the figure 14 has pivotal connection with the members 10 and 11 at the points 19 and 20 respectively. Thus it will be apparent that the members 10 and 11 can be relatively op-

erated by moving the ends of the members toward and away from each other, thus imparting movement to the figures 12, 13 and 14 and whereby, when the members are moved toward each other in one direction the figures will all be thrown at a relative angle and whereby when the members are moved away from each other or in an opposed direction the figures will be again moved into different relative angles.

The first figure represents a man with arms outstretched and similarly the figure 14 represents a woman with arms outstretched, while the figure 13 lying between the outermost figures 12 and 14 is one of a horse and on which is arranged to swing or oscillate an auxiliary figure 21 in the configuration of a man or rider. The horse or figure 13 includes members 22, 23, one of which is in the shape of a tail and has pivotal connection with the figure 13 and the other of which consists of similar ears having pivotal connection with the figure 13 whereby when the figure is actuated the tail and ears will swing or oscillate to simulate the appearance of a horse in actual life. The figures 12 and 13 each have divided portions 24 which form the legs of the figures and between which the members 10 and 11 extend for pivotal connection with the said figures and the portions 24 thereof, and the said figure 14 has a cut-out portion in the rear forming a stop flange or member 25 adapted to abut against the uppermost member 10 when the figure 14 is in a turning position due to the operation of the members 10 and 11. Similarly, the figure 12 has a portion thereof forming a stop flange or member 26 which abuts against the uppermost member 10 when the members are actuated and in a certain position so that the figures 12 and 14 form the means for limiting the relative movement of the members 10 and 11, whereas they also contribute to the amusement of the toy on account of the configuration of the figures and their relation to the central figure 13 in the operation of the device. The auxiliary figure 21 has a front portion 27 thereof adapted to abut against the figure 13 to limit the forward sliding movement of the auxiliary figure and, similarly, it has a rear portion 28 adapted to engage the figure 13 to limit the rearward swinging movement of the auxiliary figure.

Now in the operation of the device it will

be seen that when the extremities of the members 10 and 11 are grasped and pressed inwardly toward each other and then pulled outwardly in rapid succession the figures 5 will simultaneously be operated and the unitary effect to the eye will, in one position of the members 10, appear to show the rider as being thrown from the horse or central figure into the arms of the first figure 12 10 whereas when the members 10 are in their other position the rider will appear as if he is being thrown rearwardly from the horse or central figure and into the arms of the right hand figure 14, whereas, in fact, the 15 rider or the auxiliary figure 21 never leaves the central figure 13 but remains in pivotal engagement therewith. Thus it will be apparent that the outer figures limit the relative movement of the members 10 and that 20 with the provision of the members 10 and 11 the three figures 12, 13 and 14 having connection with the members 10 and 11, will be simultaneously operated to move relatively and the auxiliary figure 21 will be also actuated, although the same has no connection 25 with the members 10 and 11 but is free to swing upon one of the figures, namely, the figure 13 and which is the central figure.

From the foregoing description it will be 30 apparent that the device described is of a simple construction, consists of few parts that can be cheaply manufactured, will afford great amusement to people and in its operation comprehends the movement of two 35 similar figures whereby to actuate four figures simultaneously, three of which figures have connection with the members

whereas the fourth figure is mounted upon one of the figures having connection with the members.

Having thus described my invention, I claim:

1. In a toy, a plurality of relatively movable members, a plurality of figures having pivotal connection with the members and 45 movable when the members are actuated, said figures constituting stop members to limit the relative movement of the said members, an intermediate figure having pivotal connection with the members and 50 operable simultaneously with the first mentioned figures when the said members are actuated, and an auxiliary figure carried by the intermediate figure and freely oscillable thereon to be actuated when the said intermediate figure is operated.

2. In a toy, the combination with a plurality of members, of outer and an intermediate figure, each having independent pivotal connection with the members, with 60 the said outermost figures constituting means for limiting the relative movement of the said members, and an auxiliary figure mounted to swing on the intermediate figure and operable therewith to move toward 65 either of the said outermost figures when the said members are actuated.

In testimony whereof I affix my signature in presence of two witnesses.

FRANK J. BOYLE.
